UNITED STATES PATENT OFFICE

ADELIN H. BROUSSARD AND LOUIS K. THIEODEAUX, OF NEW ORLEANS, LOUISIANA

RAIL JOINT

Application filed March 5, 1929. Serial No. 344,381.

The present invention relates to improvements in railroad joints and has for its principal object to provide an improved fastening means for positively clamping a rail or 5 the adjacent ends of a pair of alined rails in position on a tie plate against lateral and vertical movement.

One of the important objects of the present invention is to provide a rail fastening 10 means that includes the provision of a pair of locking wedges that cooperate with upstanding shoulders formed on the end portions of the tie plates and the adjacent edge portions of the respective fish plates.

Still a further object is to provide a rail 15 joint of the above mentioned character wherein the parts can be readily and easily assembled, additional means being provided for positively securing the slidably locking wedges in their properly adjusted positions.

Another object is to provide a rail joint of 20 the above mentioned character which is simple in construction, inexpensive, strong and durable and further well adapted to the purpose for which it is designed.

Other objects and advantages of the invention will become apparent from the following description when taken in connection with the accompanying drawing.

In the accompanying drawing wherein like reference characters indicate corresponding parts throughout the several views:

Figure 1 is a detail perspective view of the rail joint embodying our invention.

Figure 2 is a longitudinal sectional view through the joint.

Figure 3 is a fragmentary detail perspective view of one end portion of the base or tie plate.

Figure 4 is a detail perspective view of one of the fish plates, and

Figure 5 is a similar view of one of the locking wedges.

In the drawing wherein for the purpose of 45 illustration is shown the preferred embodi-

ment of our invention, the numeral 1 designates a substantially elongated steel tie plate that is provided at its respective ends with suitable openings to accommodate spikes 2 whereby the tie plate may be fixedly secured 50 on the wooden tie 3 in the manner as suggested very clearly in Figures 1 and 2.

Formed on the upper face of the tie plate 1 inwardly of the respective ends thereof are the transverse shoulders 4 and 5, respectively, 55 and these shoulders extend for the full width of the tie plates. Each of these shoulders gradually decreases in width from one end thereof to the other end and the inner opposed edge portions of these shoulders are 60 formed with the longitudinally extending substantially V-shaped channels 6 for a purpose to be presently described.

The rail A has its base B resting across the upper face of the intermediate portion 65 of the tie plate 1 and where the device is used for connecting the abutting ends of a pair of alined rails, said adjacent ends of the rails have their base portions resting on the upper face of the intermediate portion of the 70 tie plate.

A pair of fish plates such as are shown at 7 in Figure 4 of the drawing are arranged on opposite sides of the rail A and the outer edge of the horizontal portion 8 of each fish plate terminates in spaced relation with respect to the inner edge of the respective shoulder formed on the tie plate 1 and furthermore, the outer edge of the horizontal portion 8 is 75 also provided with a V-shaped channel 9 similar to the channel 6 formed in the inner longitudinal edge of each shoulder.

The inner portion of the base or horizontal portion 8 of each fish plate 7 extends over the 85 respective base flange of the rail, while the upstanding portion 10 engages with the respective side of the web portion of the rail. The upper edge of the upstanding portion 10 is adapted to engage with the under side 90

of the head of the rail in the manner as clearly indicated in the drawing.

Laterally extending pins 11 project inwardly from each of the upstanding portions 10 for disposition within suitable recesses provided therefor in the web portion of the rail.

Also forming a salient part of the present invention are the locking wedges shown generally at 12 in Figure 5. A pair of such wedges is employed, and the longitudinal edges portions of each wedge are beveled as indicated at 13. Each locking wedge is furthermore formed with a pair of vertical openings 14, the purpose of which will be presently described.

The wedges 12 are driven between the adjacent edges of the shoulders 4, and the respective angle or fish plates 7, the beveled edges 13 being adapted for cooperation with the respective V-shaped channels whereby to positively secure the fish plates 7 in engagement with the respective sides of the rail or rails to positively secure the same on the tie plate against lateral and vertical movement.

For the purpose of securing the locking wedges in their properly adjusted positions on the tie plates, I employ the spikes 15 that are driven through the openings 14 and through the elongated slots 16 formed in the tie plate 1, the pointed ends of the spikes being driven into the wooden tie 3 as clearly shown in Figure 2.

When the parts are arranged as shown in Figures 1 and 2, the rails are positively secured in position against creeping and due to the simplicity of my construction, the parts can be readily and easily assembled as well as manufactured at a low cost.

A rail joint of the above mentioned character will at all times be positive and efficient in carrying out the purposes for which it is designed.

While we have shown the preferred embodiment of our invention it is to be understood that minor changes in the size, shape and arrangement of parts may be resorted to without departing from the spirit of the invention and the scope of the appended claim.

Having thus described the invention, what we claim as new and desire to secure by Letters Patent is:—

In combination, a tie, a tie plate secured on the upper face thereof, the intermediate portion of the upper face of the tie plate providing a seat supporting a rail, shoulders formed on the upper face of the respective end portions of the tie plate, the inner edge of each shoulder being inclined gradually from one end thereof to the other end, the inner edge of each shoulder being formed with a V-shaped channel, a pair of fish plates for disposition on the tie plate on opposite sides of the rail, the outer ends of the horizontal portions of said fish plates being spaced with

respect to the inclined inner edges of the respective shoulders, the outer edge of the horizontal portion of each fish plate being inclined gradually from one end to the other and being formed with a V-shaped channel, and locking wedges slidably fitted between the outer ends of the horizontal portions of the fish plates and the respective shoulders, the longitudinal edges of the locking wedges being beveled for cooperation with said V-shaped channels, and means for positively securing the locking wedges in their adjusted positions.

In testimony whereof we affix our signatures.

ADELIN H. BROUSSARD.
LOUIS K. THIBODEAUX.
